UNITED STATES PATENT OFFICE.

FREDRIC M. PARKER, OF WORCESTER, MASSACHUSETTS, ASSIGNOR TO
WILLIAM JAMES HOGG, OF SAME PLACE.

DESIGN FOR CARPET.

SPECIFICATION forming part of Design No. 24,305, dated May 14, 1895.

Application filed April 5, 1895. Serial No. 544,676. Term of patent 3½ years.

To all whom it may concern:

Be it known that I, FREDRIC M. PARKER, a citizen of the United States, residing at Worcester, in the county of Worcester and 5 State of Massachusetts, have invented and produced a new and original Design for Carpets, of which the following is a specification.

My invention relates to a design to be worked into or upon carpeting or similar fabrics, and I do hereby declare that the drawing accompanying this specification gives and conveys to any person skilled in the art of carpet weaving a sufficiently clear understanding of the same to enable such person to use 15 my invention.

The drawing is a face view of a carpet embodying my new design.

The drawing illustrates a body and a border.

The body A is characterized by festoons of 20 conventionalized lace, small floral figures which rest upon or appear to cross behind the festoons, and larger detached floral figures arranged between the branches of the festoons.

The border B is characterized by somewhat 25 narrower lace festoons than those in the body, and by floral figures which conform to those employed in the body.

The colors employed for the different portions of this design may be varied to suit the 30 taste and convenience of the manufacturer.

What I claim, and desire to secure by Letters Patent of the United States, is—

1. In a design for carpeting, the body A, substantially as shown. 35
2. In a design for carpeting, the border B, substantially as shown.
3. The design for carpets consisting of the body A and the border B, substantially as shown. 40

In testimony whereof I have hereunto set my hand in the presence of two subscribing witnesses.

FREDRIC M. PARKER.
